Primary Examiner — Kelley Donnelly

(74) *Attorney, Agent, or Firm* — Hubbard Johnston,
PLLC

(57) **CLAIM**

The ornamental design for a rack shelf, as shown and described.

DESCRIPTION

FIG. 1 is a top perspective view of a rack shelf;
FIG. 2 is a top plan view of rack shelf of FIG. 1;
FIG. 3 is a bottom plan view of the rack shelf of FIG. 1;
FIG. 4 is a front elevational view of the rack shelf of FIG. 1;
FIG. 5 is a rear elevational view of the rack shelf of FIG. 1;
FIG. 6 is an elevational view of a first side rack shelf of FIG. 1; and,
FIG. 7 is an elevational view of a second side of the rack shelf of FIG. 1.

1 Claim, 4 Drawing Sheets
